UNITED STATES PATENT OFFICE.

LEWIS GRISCOM, OF POTTSVILLE, PENNSYLVANIA.

OSCILLATING ENGINE.

SPECIFICATION forming part of Letters Patent No. 253,038, dated January 31, 1882.

Application filed November 21, 1881. (No model.)

To all whom it may concern:

Be it known that I, LEWIS GRISCOM, a citizen of the United States, residing in Pottsville, Schuylkill county, Pennsylvania, have invented 5 an Improvement in Oscillating Engines, of which the following is a specification.

The object of my invention is to increase the port area of an oscillating engine without a corresponding increase in the extent of oscillation 10 of the cylinder; and this object I attain in the manner which I will now proceed to describe, reference being had to the accompanying drawings, in which—

Figure 1 is a perspective view of the cylinder 15 and standards of an oscillating engine, one of the standards being detached and reversed in order to show the ports; Fig. 2, a face view of the cylinder-trunnion and its port; Fig. 3, a 20 face view of the ports in the standard, and Figs. 4 and 5 diagrams illustrating the relation of the ports to each other as the cylinder oscillates.

A is the cylinder of the engine, and B B the opposite vertical standards, between which the cylinder is hung and oscillates, said cylinder having trunnions *a*, with central journals, *b*. These journals are adapted to bearings *d*, formed in the upper ends of the standards B, and in circular bosses *e* on the latter, suitable means 25 being provided for maintaining the faces of the trunnions *a* and bosses *e* in steam-tight contact with each other.

In an oscillating engine having a single port only in each end of the cylinder the area of 30 port-opening is necessarily limited by the extent of oscillation of the cylinder, and in short-stroke engines the ports are unduly contracted.

The object of my invention is to overcome this difficulty; and in carrying out my invention I adopt the arrangement of ports which I 35 will now proceed to describe.

In either or both of the cylinder-trunnions *a* are formed two sets of ports, *f f' f²* and *i i' i²*, the ports *f f' f²* communicating with the front 40 end of the cylinder, and the ports *i i' i²* communicating with the rear end of the same.

Either or both of the standards B are divided at the upper end by a partition (shown by dotted lines in Fig. 3) into a steam-chamber, D, 45 and an exhaust-chamber, E, the boss *e* having ports *m m'* and *n n'* communicating with the

steam-chamber D, and ports *x x'* and *y y'* communicating with the exhaust-chamber E. The ports *m m'* and *x x'* are so located as to work in connection with the ports *f f'* and *f²* of the cylinder, and the ports *n n'* and *y y'* are adapted to work in connection with the ports *g g'*, and *g²* of the cylinder in the following manner: When the trunnion *a* of the cylinder occupies the position shown in Fig. 4 the ports *f f'* coincide with the ports *m m'*, and the port *f²* occupies a position between the ports *x x'*, the ports *i i²* coinciding with the ports *y y'* and the port *i* occupying a position between the ports *n n'*. Steam from the chamber D thus enters the 55 front end of the cylinder through the ports *f f'* and *m m'*, and is exhausted from the opposite end of the cylinder through the ports *i i²* and *y y'* and chamber E, the ports *i* and *f²* being blind ports—that is to say, serving neither 60 as steam nor exhaust ports. When the cylinder is in this position the piston is at half-stroke and is moving rearward, and as said cylinder oscillates on its trunnion bearings the 65 relation of the ports in the cylinder to those in the standard B changes until, when the piston has reached mid-stroke in a forward direction, the ports occupy the relations shown in Fig. 5, steam entering the rear end of the cylinder through the ports *i i'* and *n n'*, and being exhausted from the front end of the cylinder through the ports *x x'* and *f f'*, the ports *i i²* and *f f²* working blind between the ports *y y'* and *m m'*, respectively.

It will be seen that the center port, *i* or *f*, 75 of the cylinder is always an acting port, and is re-enforced by one of the other ports of the set both in supplying steam to and exhausting it from the cylinder, the remaining port of the 80 set working blind.

The rule to be observed in laying out the ports is that the distance between the ports *m* and *x* and *n* and *y* shall be less by a little more than the width of a port than the distance between the ports of a cylinder, or between the 85 ports *m* and *m'*, *n* and *n'*, *x* and *x'*, or *y* and *y'*, so that while the center ports of the cylinder are caused by the movement of said cylinder to coincide alternately with the steam and exhaust ports, the upper and lower ports of the 90 set alternately act as blind ports. The same principle may be applied to engines having more 100

than three cylinder-ports in each set. For instance, the cylinder may have five ports in a set, and the standard may have three steam and three exhaust ports in each set, instead of 5 two, as in the drawings, there being in this case two blind ports in each set of cylinder-ports, and by the same rule the number of ports may be increased as desired.

I have described my invention as applied to 10 a steam-engine; but it may be applied to air or gas engines as well, the invention being, as above set forth, especially advantageous in engines of short stroke, where the oscillating movement is of limited extent and the ports 15 are necessarily contracted in width.

I claim as my invention—

The combination of the standard B of the engine, having two sets of steam and exhaust ports spaced as described with the cylinder having two sets of ports spaced in respect to 20 those of the standard as set forth, whereby the ports above and below the center port serve alternately as blind ports and acting ports, as set forth.

In testimony whereof I have signed my name 25 to this specification in the presence of two subscribing witnesses.

LEWIS GRISCOM.
